Primary Examiner — Marianne Pandozzi*Assistant Examiner* — Jae Liang(74) *Attorney, Agent, or Firm* — Hamilton, Brook, Smith & Reynolds, P.C.(57) **CLAIM**

The ornamental design for a beverage container, as shown and described.

DESCRIPTION

FIG. 1 is an upper perspective view of a beverage container showing our new design;

FIG. 2 is a lower perspective view thereof;

FIG. 3 is a side elevational view thereof;

FIG. 4 is a top view thereof; and,

FIG. 5 is a bottom view thereof.

The broken lines in the drawings depict portions of the beverage container that form no part of the claimed design. The article is a beverage container for retail sale.
